ESCUTCHEON FOR AN ELECTRICAL SWITCH

Harry L. Stillman, Chicago, Ill., assignor to Bell Electric,
Chicago, Ill., a corporation of Illinois

Filed Oct. 21, 1965, Ser. No. 87,667

Term of patent 14 years

(Cl. D26—13)

FIG. 1.

FIG. 2.

FIG. 4.

FIG. 3.

FIG. 5.

FIG. 1 is a front elevational view of an escutcheon for an electrical switch, showing my new design;

FIG. 2 is a side elevational view thereof;

FIG. 3 is a bottom plan view thereof;

FIG. 4 is a rear elevational view thereof; and

FIG. 5 is a cross-sectional view thereof, taken on line 5—5 of FIG. 1.

Portions of the drawing figures are stippled to indicate contrast in appearance.

I claim:

The ornamental design for an escutcheon for an electrical switch, as shown and described.
